GEOCHEMICAL PROSPECTING

Esme E. Rosaire, Houston, Tex.

No Drawing. Application July 20, 1940,
Serial No. 346,520

3 Claims. (Cl. 23—230)

The present invention is directed to a method of geochemical prospecting and geochemical well logging and particularly to that method which involves the collection of samples of soil, the recovery of a gas sample from each soil sample and the analysis of each gas sample. The method at present finds its greatest applications in geochemical well logging, but is also applicable to areal geochemical surveying.

In geochemical well logging and, to a somewhat lesser degree, in geochemical surface prospecting, experience has shown that the interval of time between the collection of the sample and its analysis has some bearing on the concentrations of significant constituents found. For a long time, particularly in geochemical well logging, it was thought that the length of this period was not a matter of particular importance. Such is actually the case where the sample of soil contains, for example, only methane. However, where the soil sample contains heavier hydrocarbons, particularly pentane and higher, it tends to lose these higher hydrocarbons on standing. For example, if a portion of a cutting sample containing methane and higher hydrocarbons is analyzed immediately after collection and another portion of the same sample is allowed to stand for a period such as a week and analyzed, it is frequently found that the methane contained in the cuttings does not diminish appreciably while the content of the heavier hydrocarbons has decreased tremendously and sometimes has disappeared entirely.

It does not appear that this phenomenon was due to evaporation alone, though there may be some vapor pressure relationship between the higher hydrocarbons such that the higher hydrocarbons would disappear while methane would not be lost to a substantial degree. But there are possible explanations for the loss of hydrocarbons in these samples other than evaporation. A consideration of these other possibilities would not serve any purpose for the reason that the exact cause is not known.

These losses can be avoided if the soil samples, immediately upon collection, are reduced in temperature, as by being placed in a container of dry ice or by being placed in a refrigerator. This preservation of the sample is of extreme importance because in actual practice, particularly in well logging, it is often difficult to analyze the

samples as soon as they are obtained, because, for example, the well may be in the process of drilling in a remote area where it is difficult to move analytical equipment. This is also true where long distances separate the drilling well and the laboratory. Another advantage of importance exists when samples are collected at a given time for analysis later during off-peak laboratory periods. For example, samples for geochemical analysis may be collected during seismic prospecting operations, and for economy's sake analyzed at convenient later times. Obviously a safe storage technique becomes of great value.

10 According to the present invention, therefore, the samples, immediately upon their recovery, such as samples in the form of cuttings, are placed in a container together with dry ice, or surrounded by dry ice. Alternatively, a portable

15 refrigerator may be employed. It has been indicated that a reduction in temperature to about 0° centigrade is sufficient for the preservation of the sample, although I prefer to lower the temperature sufficiently to freeze 20 any moisture in the sample. Naturally the sample should be maintained at such low temperature both during transport to the laboratory and in storage until such time as it is analyzed.

25 The nature and objects of the present invention having been thus described and illustrated, what is claimed as new and useful and is desired to be secured by Letters Patent is:

30 1. In geochemical prospecting in which samples of soil are collected for the purpose of recovering therefrom a gas to be analyzed for significant constituents the step of subjecting the soil samples immediately upon recovery to such substantially reduced temperature that such constituents as are otherwise subject to loss at ordinary temperatures are retained in the samples and holding the samples at this reduced temperature until they are subjected to a treatment for the recovery therefrom of the gas to be analyzed.

35 2. The method according to claim 1 in which the reduced temperature is not substantially above 0° centigrade.

40 3. The method according to claim 1 in which the temperature is reduced quickly to below 0° centigrade.

ESME E. ROSAIRE.
